UNITED STATES PATENT OFFICE.

GEORGE POTTS, OF INDIANAPOLIS, INDIANA.

TILE-MACHINE.

SPECIFICATION forming part of Letters Patent No. 274,514, dated March 27, 1883.

Application filed November 10, 1882. (No model.)

To all whom it may concern:

Be it known that I, GEORGE POTTS, a citizen of the United States, residing in the city of Indianapolis, county of Marion, and State of Indiana, have invented certain new and useful Improvements in Tile-Machines, fully described and represented in the following specification and the accompanying drawings, forming a part of the same.

10 This invention relates to a mechanism for the manufacture of tiles for draining and analogous purposes, it being the object of the invention to produce a mechanism for this purpose which shall be more rapid and reliable in its operation, capable of producing a better article, and of being operated with a less expenditure of power than those heretofore in use.

20 To this end the invention consists in various details of construction and combinations of parts in the machine, all of which will be hereinafter fully explained and particularly pointed out.

In said drawings, Figure 1 is a longitudinal vertical section of a mechanism embodying the invention. Fig. 2 is an end elevation of the same. Fig. 3 is an end view of the die-chamber, showing the interior and exterior dies and the manner of adjusting and holding the same in position. Fig. 4 is a horizontal section taken upon the line $x-x$ of Fig. 1. Fig. 5 is a side elevation of the driving-cylinder, showing also the reversing mechanism. Fig. 6 is an enlarged view of a portion of Fig. 5. Figs. 7 and 8 are sectional details of the valve for controlling the feed of oil to the driving-cylinder. Fig. 9 is an inside view of the interior and exterior dies, showing the interior die supported in a different manner; and Fig. 10 is a perspective view of a section of the tile produced.

The cylindrical tempering-hopper A is mounted in the usual manner above the die-chamber B, and is provided at a point near its top with a feeding-opening, 1, for the reception of the clay. This hopper is also provided with a vertical shaft, 2, carrying the tempering-blades 3, said shaft and blades being connected by suitable gears, as 4 5, with a shaft carrying the 45 driving-pulley 6.

At the bottom of the tempering-hopper the

die-chamber is provided with an opening, 7, through which the clay falls after it is properly tempered and in condition to be pressed through the opening formed by the dies. 55

It will be observed that the bearing 8, through which the tempering-blade shaft passes at the top of the tempering-hopper, is of sufficient length to entirely support said shaft, so that a bearing at its bottom is dispensed with, by 60 reason of which the opening 7 is left entirely unobstructed and a free passage afforded for the clay from the hopper to the die-chamber.

The die-chamber B is shown, in the present case, as square in cross-section, although it 65 may be of polygonal or of cylindrical form, and is of suitable diameter and length to receive the desired quantity of clay and to permit the plunger to have the proper length of stroke. The forward end of the die-chamber is provided with the various parts constituting the die, through which the clay is pressed to give the proper shape to the tile. These parts consist of an interior die, an exterior die, and an adjustable supporting-frame carrying the latter. 70 The interior die, 10, around which the tile is formed, and which serves to determine its interior configuration, is removably supported upon an arm or bracket, 11, which may be of the form shown in Fig. 1, and secured by bolts 12 to 75 one side of the interior of the die-chamber. This support may, however, extend across and be secured to both sides of the chamber, as shown in Fig. 9 and by dotted lines in Fig. 1. The exterior die, 13, through which the tile 80 passes, and which serves to determine its exterior configuration, is seated in an opening in the supporting-frame or die-carrier 14, it being secured to said frame by a series of buttons or catches, 15, as clearly shown in Fig. 3. The carrier or frame 14, supporting the exterior die, is 85 adjustably secured to the forward end of the die-chamber by means of the series of bolts 16, which pass through flanges upon the sides of the chamber and enlarged openings 17 in said 90 frame, as shown in Fig. 1.

To aid in properly adjusting the frame 14 and securing it in any adjusted position, the end of the die-chamber is provided with the series of projecting ears 18, through which pass set-screws 19, the inner ends of which abut against said frame and support it upon all 95 100

sides. By means of these devices it will readily be seen that the exterior die can be set in any desired relation to the interior die, so as to produce tile of uniform thickness upon all sides, 5 or of uneven thickness, which latter is often desirable. It will also be seen that by changing the interior or exterior die, or both, which can readily be done, thicker or thinner or larger or smaller tile can be produced at pleasure, and also that dies of different forms may be substituted, so as to vary the exterior or interior configuration of the tile, or both.

The novel features of the parts just described are not herein claimed, as they will 15 form the subject-matter of a future application for Letters Patent.

The reciprocating plunger with which the die-chamber is provided, and by which the clay delivered from the tempering-hopper is 20 pressed through the opening in the die, consists essentially of a pair of heads, 20 21, connected by a yoke, 22, and a top plate, 23. The heads 20 21 fill the entire area of the chamber, substantially like pistons, and the head 20 is 25 provided with an ordinary flap or other valve, 24, so arranged that, as the plunger moves backward, air will be allowed to enter the die-chamber and prevent the formation of a vacuum in front of the plunger. The plate 23, 30 which connects the front and rear heads of the plunger, extends the entire width of the die-chamber, or is at least of sufficient width to cover the opening 7 and prevent the clay from falling in the rear of the head 20 when the 35 plunger is at the forward end of its travel. This plate is also made slightly adjustable by means of set-screws 25, so that it can be moved outward to compensate for wear.

The bottom of the die-chamber is provided 40 with an opening, 26, located as shown in Figs. 1 and 4, through which the interior of the chamber can be reached for the adjustment of the parts.

The plunger just described is operated to 45 press the clay through the opening in the die by means of hydraulic or other analogous pressure applied from the cylinder 28 upon the rear end of the die-chamber through the piston 29 and piston-rod 30, the latter of which 50 passes through the head 21, and is secured to the yoke 22, as clearly shown in Figs. 1 and 4.

The fluid, (preferably oil or some other substance which is nearly or quite non-compressible,) which drives the piston 29, is forced into the 55 cylinder 28 through a main pipe, as 31, connected with any appropriate form of pumping apparatus operated either from some moving part of the machine or independently thereof, as may be desired. In the present case this 60 pumping apparatus is shown as consisting of a double force-pump, 32, the pistons 33 whereof are connected with and driven by eccentrics 34 upon the driving-shaft of the machine. These pumps are provided with valves, so arranged 65 in the ordinary manner that the motion of their pistons draws the oil or other fluid from the

tank 35, through pipe 36 and chamber 37, into the pumps, and ejects the same through chamber 38 and pipe 27 into the pipe 31. One end of the main pipe 31 enters and terminates near 70 the top of the tank 35, as shown in Fig. 1, at which point it is provided with a safety-valve, 39, controlled by a spring or other device which can be adjusted, so that in case the plunger meets with any undue resistance, as would happen 75 if a stone or other solid substance should pass into the die-chamber, a relief may be afforded to the pressure of the fluid in the cylinder 28 and all danger of breaking the machine be avoided. This pipe also communicates with 80 an air-chamber, 40, in which the elasticity of the confined air serves to make the movements of the piston regular and uniform. The opposite end of the pipe 31 enters the valve-chamber 41, which contains an oscillating valve, 42, 85 which operates to direct the oil or other fluid alternately through the pipes 43 44 and into the cylinder 28 upon the opposite sides of the piston 29.

Referring particularly to Figs. 7 and 8, it will 90 be seen that the valve-chamber 41 consists of a cylindrical casing provided with ports 45 46 47, communicating respectively with pipes 31 43 44, and with a port, 48, communicating with the exhaust-pipe 49, through which the motor-fluid is returned to the tank 35. The valve 42 consists of a slightly-tapering cylindrical plug provided with parallel passages 50 51, which may be made to communicate with ports 46 47 and branch passages 52 53, which open into 100 ports 45 48. To give greater strength to the plug the passages 50 51 52 53 are provided with a partition-wall, 68, as shown in Fig. 7. This plug is provided with a stem, 54, extending through the wall of the valve-chamber, and 105 with adjusting-screws 55 56, located as shown, by which it can be maintained in such position as to preserve a perfectly-tight joint between it and the casing.

The stem 54 is provided with an arm, 57, 110 (see Fig. 5,) which is connected by a link, 58, with a pivoted lever, 59, the end of which is loosely connected to a collar, 60, which slides freely upon the valve-rod 61, which is connected to the head 21 of the plunger. The rod 61 115 is provided with two adjustable collars, 62 63, which, by means of set-screws, can be secured to the rod in any desired position, and is also provided between said collars with springs 64 65, the purpose of which will hereinafter appear. The end of the lever 59 extends below the collar 60, and engages with the face of a double-inclined block, 66, which slides in suitable ways secured to the side of the cylinder 28, and is pressed upward against the 125 end of said lever by a spring, 67, as shown in Figs. 5 and 6.

The operation of the mechanism just described is as follows: The clay, being introduced through the opening 1 into the tempering-hopper, will pass gradually downward in 130 said hopper, being tempered during its pas-

sage by the blades 3. As it arrives at the bottom of the hopper the tempered clay passes through the opening 7 into the die-chamber in front of the plunger. When a sufficient quantity of the clay has thus passed into the die-chamber, the pumps will be started, and the fluid forced into the cylinder 28, behind the piston 29, will cause the plunger to advance, thereby forcing said clay through the die-opening and forming the tile, as shown in Fig. 5. When the plunger has thus advanced a proper distance the spring 65 will come into contact with the collar 60, and said spring will be compressed until it has acquired sufficient tension to move the lever 59 against the resistance of the inclined block 66. As soon as the lever 59 is started the expansion of the spring 65 will throw its end quickly over the apex of the block 66, when the expansion of the spring 67 will at once raise the block to its normal position. This movement of the lever 59 will, through link 58 and arm 57, turn the valve 42, so as to permit the fluid forced into the pipe 31 to pass through port 45, passages 52 50, 25 port 46, and pipe 43 into the cylinder in front of the piston 29, to retract the plunger. At the same time that a passage is thus opened for the admission of the fluid to the cylinder in front of the piston a passage will be opened 30 through pipe 44, port 48, passages 53 51, port 47, and pipe 49, which will permit the fluid in the rear of the piston to pass back to the tank 35. When the piston has gained the rear end of its stroke the spring 64 will come into contact with the collar 60, and the valve will in like manner be moved in the opposite direction, so as to admit the fluid through port 45, passages 52 50, port 47, and pipe 44 to the cylinder behind the piston, thereby causing the 40 plunger to again advance, while at the same time the fluid in front of the piston will be allowed to escape through pipe 43, port 46, passages 51 53, and port 48.

It will be observed that by reason of the 45 cylindrical sleeve 69, which surrounds the piston-rod in front of the piston, the front area of the piston is reduced to one-third or less than one-third of its rear area, from which it results that the piston and plunger are retracted very much more rapidly than they are advanced, thus effecting a great increase in the rapidity of the operation of the machine.

It is to be observed that the partition 70, which separates the passages 50 51 in the valve, 55 is slightly less in thickness than the diameter of the ports 46 47, from which it results that in reversing the piston there is never a time when the passage of the fluid through the valve is entirely arrested, it being allowed to 60 enter the passage 50 before it is entirely shut off from the passage 51, and vice versa. This feature relieves the strain to which the valve would be subjected by totally arresting the flow of the fluid.

65 It will readily be seen that by varying the positions of the collars 62 63 the length of the

stroke of the piston and plunger and the amount of clay delivered through the die can be regulated at pleasure.

As before stated, the pump 32 may be of any approved construction, and may be operated by or independently of the machine.

Instead of a double pump, as shown, a single pump may be used, although the former is preferable, as it gives a uniform movement to 75 the plunger.

By varying the quantity of fluid fed to the pump, for which purpose the pipe 36 is provided with a regulating-cock, as shown in Fig. 1, or pumps, it will readily be seen that the speed of the plunger can be varied at pleasure. This is an important feature, as in making tile of large size the plunger can be operated successfully at a much greater speed than when small-sized tile are being made, and also 85 because by this means the amount of tempering to which the clay is subjected can be easily regulated.

What I claim is—

1. The combination, with the tempering-hopper and its tempering-blades, of the die-chamber and its plunger, and means for operating said blades and plunger and for varying their speed with relation to each other, substantially as described. 90

2. The combination, with the tempering-hopper and its blades, of the die-chamber and its plunger, the fluid-cylinder and its piston, and the pump and its connecting-pipes, the whole being arranged and operating substantially as described. 95

3. The combination, with the tempering-hopper and its blades, of the die-chamber and its plunger, the fluid-cylinder and its piston, the pump and its connecting-pipes, and the supply-pipe 36, provided with a regulating-cock, the whole being arranged and operating substantially as described. 105

4. The combination, with the tempering-hopper and its blades, of the die-chamber and the plunger, provided with the adjustable plate 23, substantially as and for the purpose set forth. 110

5. The combination, with the tempering-hopper and its blades, of the die-chamber and its plunger, and means for retracting said plunger at a speed greater than that with which it is advanced, all substantially as described. 115

6. The combination, with the tempering-hopper and its blades, of the die-chamber and its plunger, and means for varying the stroke of said plunger, all substantially as described. 120

7. The combination, with the tempering-hopper and its blades, of the die-chamber and its plunger, the fluid-cylinder and its piston, the front area of which is less than the rear, and means for delivering the fluid with the same rapidity to both sides of said piston, all substantially as described. 125

8. In a tile-machine, the combination, with the die-chamber and its plunger, of the fluid-

cylinder and its piston, and the pipe, as 31, provided with a safety-valve, as 39, the whole being arranged and operating substantially as described.

- 5 9. In a tile-machine, the combination, with the die-chamber and its plunger, of the fluid-cylinder and its piston, the valve, as 42, the valve-rod attached to said plunger, and provided with adjustable collars, as 62 63, and 10 springs, as 64 65, and the connections, the whole being arranged and operating substantially as described.
- 10 10. In a tile-machine, the combination, with

the die-chamber and its plunger, of the piston and cylinder 29 28, valve 42, valve-rod 61, 15 attached to said plunger, and provided with the adjustable collars 62 63 and springs 64 65, the double-inclined block 66, spring 67, and connections, all substantially as described.

In testimony whereof I have hereunto set my hand in the presence of two subscribing witnesses.

GEORGE POTTS.
